UNITED STATES PATENT OFFICE.

WILLIAM H. NICKERSON, OF BROOKLINE, MASSACHUSETTS.

MACHINE FOR MAKING NONMETALLIC SHANK STIFFENERS.

Application filed January 29, 1926. Serial No. 84,600.

This invention relates to shoe-shank stiffeners usually made of wood, each stiffener being oblong, its longitudinal edges being formed by transversely grooving or scoring

5 a strip or ribbon of wood of indeterminate length to sever from the strip an oblong section of suitable size for a shank stiffener, the length of which is determined by the width of the strip. The strip is usually
10 molded before it is cut up into stiffeners, so that one side has a salient curvature, and the other side a reentrant curvature, a stiffener cut from the strip being therefore, longitudinally curved or arched, one side having
15 a salient, and the opposite side a reentrant, longitudinal curvature.

The object of the invention is to provide a simple and effective machine, adapted to rapidly cut up a strip characterized as above 20 stated, into longitudinally curved or slightly arched shank stiffeners, the form of the curved sides of the stiffeners being determined by the form of the sides of the strip, while the form of the longitudinal edges of
25 the stiffeners is determined by grooving cutters which sever the strip.

Of the accompanying drawings forming a part of this specification:

Figure 1 is a top plan view of a machine 30 embodying the invention.

Figure 2 is a fragmentary section on line 2-2 of Figure 1.

Figure 3 is a side view of the machine.

Figure 4 is a fragmentary section on line 35 4-4 of Figure 2, and a top plan view of the cutter.

Figure 5 is a fragmentary section on line 5-5 of Figure 4, and a side view of the cutter.

40 Figure 6 is a view similar to Figure 4, showing a different stage of the operation.

Figures 7 and 8 are side and edge views of a completed stiffener.

Figure 9 is a section on line 9-9 of Figure 45 7.

Figure 10 shows in perspective a portion of a strip prepared for severing into stiffeners.

Figure 11 is a fragmentary plan view, 50 showing in plan, a portion of the cutter head and cutters formed differently from those shown by preceding figures.

Figure 12 is a section on line 12-12 of Figure 11.

55 Figure 13 is a top plan view, showing a

plurality of machines or units, grouped around a single cutter head.

The same reference characters indicate the same parts in all of the figures.

The machine hereinafter described is 60 adapted to act on an elongated strip or ribbon 15 of wood, a portion of which is shown in perspective by Figure 10. In this figure the dotted lines indicate the transverse cuts made by the grooving cutters hereinafter described, each cut severing a completed shank stiffener from the strip. The strip is prepared for the machine by molding it while in a moist and flexible condition, to 65 impart to one of its sides a reentrant curvature, and to its opposite side a salient curvature. The reentrant side of the strip is preferably reduced, to form thin longitudinal edges on the strip, as best shown by Figures 6 and 10.

70 The machine comprises a rotary cutter head 16, having grooving cutters 17, projecting from the periphery of the head, and formed as shown by Figures 4 and 5, to cut a V-shaped groove 18, extending from edge 75 to edge of the strip, and severing from the body of the strip a shank stiffener 15^a, which has the form shown by Figures 7, 8 and 9, the bevelled edges of the stiffener shown by Figure 9, being formed by the cutters 17. 80 The cutters preferably project radially from the periphery of the head 16, and are provided with shanks confined by set screws 19 (Figure 1) in radial sockets formed in the head. The cutters are revolved in a circular path indicated by the dotted line 20 in Figure 6. The cutter head 16 is fixed to a preferably vertical shaft 21, journaled in bearings in a frame 22, and driven by any suitable means, such as a crossed belt 26, running on 85 a pulley 23 (Figure 1), fixed to a driving-shaft 24, and on a pulley 25, fixed to the shaft 21.

90 27 designates a bed block having a reentrantly curved face 28, having the same curvature as the path 20 of the cutters. The bed block 27 is movable, to alternately project the face 28 into the path 20, as shown by Figures 4 and 5, and retract the face from said path, as shown by Figure 6; the block 95 being moved on fixed guides 29, on the frame by means hereinafter described. The strip 15 is held in close contact with the curved face 28, by a presser 30, when the block is projected. Said presser is prefera- 100 105 110

bly a finger fixed to a shank 31, which is movable in a fixed guide 32 (Figure 3) on the frame, and is yieldingly pressed outward by a spring 33.

- 5 The strip 15 is fed endwise step by step, crosswise of the face 28, by a movable feeding device adapted to engage the strip, said feeding device being preferably embodied in serrated feed rolls 34 and 35, bearing on 10 opposite sides of the strip, as shown by Figure 2. The feed rolls are fixed to shafts 36 and 37, journaled in suitable bearings and connected by intermeshing gears 38 (Figure 1) fixed to the shafts.
- 15 I provide mechanism common to the feed rolls and the bed block, including means for moving the feed rolls to alternately feed and arrest the strip, and means for alternately projecting and retracting the bed 20 block, the block being retracted as shown by Figure 6, to permit the feeding of the strip while the latter is out of the path of the cutters, and projected, as shown by Figure 4, after the feeding of the strip, to permit the 25 severing of the strip by the cutters. The preferred embodiment of said mechanism is as next described.

Fixed to the feed roll shaft 36 is a ratchet 40, engaged by a spring-pressed pawl 41, 30 pivoted to a pawl carrier 42, which is slidable on fixed guides 43 on the frame. 44 designates a vertical operating shaft journaled in fixed bearings on the frame, and driven by a belt 26^a running on a pulley 25^a 35 on the cutterhead shaft 21, and on a pulley 44^a fixed to the operating shaft 44. The operating shaft is provided with a disk 45, to which is eccentrically secured a wrist-pin 46, connected by a rod 47 with the pawl carrier 42. The carrier is reciprocated by the wrist-pin and rod, so that the pawl intermittently rotates the feed rolls, which therefore alternately feed and arrest the strip 15.

To the operating shaft 44 is fixed an eccentric 48 embraced by a collar or strap 49, which is connected by a rod 50 with the bed block. The arrangement of the eccentric, its strap, and the connecting rod 50, is such that the bed block is held alternately retracted, to permit the feeding of the strip while the latter is out of the path of the cutters, and projected after the feeding of the strip, to permit the severing of the strip by the cutters.

55 The main portion of the strip 15 may be supported in the form of a roll (not shown) above the feed rolls, the strip passing, as unrolled, to the nip of the feed rolls. The edges of the strip may be guided by fixed 60 slotted guides 52, immediately above the rolls.

Instead of the independent spaced apart cutters 17, I may employ grooving cutters 17^a, formed as closely spaced integral teeth 65 on a ring 53, secured to the cutter head, as

shown by Figures 11 and 12, the teeth being formed to cut a V-shaped groove.

The retraction of the bed block 27 is sufficient to release a severed stiffener, so that it is no longer clamped between the block 70 face 28 and the presser 30, so that, as indicated by Figure 6, the stiffener 15^a is free to drop through an outlet opening in the frame, when the block is retracted, the function of the presser being to ensure close contact between the back of the strip and the face 28, during the cutting operation.

The arrangement of the feed rolls relative to the path of the cutters should be such that when the bed block is fully projected, so the projecting portion of the strip 15, below the cutters, will be forced slightly forward by the bed block from the position it occupies when the bed block is retracted, so that upon the retraction of the bed block, 85 said projecting portion will spring backward out of the path of the cutters, the strip being fed while thus sprung backward. The cutters act on the strip while the latter is being moved forward, so that the severing groove is formed progressively, an initial groove being formed by one cutter and deepened by the next cutter or cutters until the groove extends through the thickness of the strip, so that a stiffener is detached. 90

A plurality of strip-supporting and feeding units, each organized as above described, may be assembled around a single cutter head 16, as shown by Figure 13, thus providing a multiple machine which includes a 100 plurality of strip-supporting and feeding units and a cutter head whose cutters cooperate with each of the units so that several stiffeners are simultaneously produced.

I claim:

1. A machine for making non-metallic shank stiffeners, comprising a rotary cutter head having grooving cutters revolved in a circular path by the rotation of the head, a bed block having a curved strip-supporting face whose curvature is the same as that of the path of the cutters, the block being movable to alternately project said face into, and retract it from the path of the cutters, a feeding device adapted to engage an elongated transversely curved strip of stiffener material, and operating mechanism common to the feeding device and the bed block and including means for actuating the feeding device to alternately feed and arrest the strip, and means for alternately projecting and retracting the bed block, said block being retracted to permit the feeding of the strip while the same is out of the path of the cutters, and projected 115 after the feeding of the strip, to permit the severing of the strip by the cutters. 120

2. A machine for making non-metallic shank stiffeners, comprising a rotary cutter head having grooving cutters revolved in a 130

circular path by the rotation of the head, a bed block having a curved strip-supporting face whose curvature is the same as that of the path of the cutters, guides on which the block is movable to alternately project said face into, and retract it from the path of the cutters, feed rolls adapted to engage an elongated transversely curved strip of stiffener material, and operating mechanism common to the feed rolls and the bed block and including means for intermittently rotating the feed rolls, to alternately feed and arrest the strip, and means for alternately projecting and retracting the bed block, said block being retracted to permit the feeding of the strip, while the same is out of the path of the cutters, and projected after the feeding of the strip, to permit the severing of the strip by the cutters.

20 3. A machine for making non-metallic shank stiffeners, comprising a rotary cutter head having grooving cutters revolved in a circular path by the rotation of the head, a bed block having a curved strip-supporting face whose curvature is the same as that of the path of the cutters, guides on which the block is movable to alternately project said face into, and retract it from the path of the cutters, feed rolls adapted to engage an elongated transversely curved strip of stiffener material, shafts carrying the feed rolls and connected by gears, a ratchet fixed to one of the feed roll shafts, a pawl carrier having a pivoted pawl engaging said ratchet, guides on which the pawl carrier is movable, to reciprocate the pawl, an operating shaft, an eccentric wrist-pin fixed to the shaft, a rod connecting the wrist-pin with the pawl carrier, the arrangement being such that the rolls are intermittently rotated and alternately feed and arrest the strip, an eccentric fixed to the operating shaft, an eccentric strap embracing the eccentric, and a rod connecting the strap with the bed block, the arrangement being such that the block is alternately retracted, to permit the feeding of the strip while the same is out of the path of the cutters, and projected after the feeding of the strip, to permit the severing of the strip by the cutters.

40 4. A machine for making non-metallic shank stiffeners, comprising a rotary cutter head having grooving cutters revolved in a circular path by the rotation of the head, a bed block having a curved strip-supporting face whose curvature is the same as that of the path of the cutters, guides on which the block is movable to alternately project said face into, and retract it from the path of the cutters, a feeding device adapted to engage an elongated transversely curved strip of stiffener material, a presser adapted to maintain the strip in contact with the bed block face, when the block is projected, and operating mechanism common to the feeding device and the bed block and including means for actuating the feeding device, to alternately feed and arrest the strip, and means for alternately projecting and re-70 tracting the bed block, said block being retracted, to permit the feeding of the strip while the same is out of the path of the cutters, and projected after the feeding of the strip, to permit the severing of the strip 75 by the cutters.

5. A multiple machine for the purpose stated, comprising a rotary cutter head having grooving cutters revolved in a circular path by the rotation of the head, and a plurality of strip-supporting and feeding units arranged to cooperate with the cutters, each unit including a bed block having a curved strip-supporting face whose curvature is the same as that of the path of the cutters, the block being movable to alternately project said face into, and retract it from the said path, a feeding device adapted to engage an elongated transversely curved strip of stiffener material, and operating mechanism common to the feeding device and the bed block, and including means for actuating the feeding device to alternately feed and arrest the strip, and means for alternately projecting and retracting the bed block, said block being retracted to permit the feeding of the strip while the same is out of the path of the cutters, and projected after the feeding of the strip, to permit the severing 80 of the strip by the cutters.

In testimony whereof I have affixed my signature.

WILLIAM H. NICKERSON.
